UNITED STATES PATENT OFFICE.

CHARLES L. BALDWIN AND OLLIE A. GREEN, OF NEW YORK, N. Y.; SAID BALDWIN ASSIGNOR TO MAUD E. BALDWIN, OF NEW YORK, N. Y.

ELEVATOR.

SPECIFICATION forming part of Letters Patent No. 709,732, dated September 23, 1902.

Application filed December 28, 1901. Serial No. 87,643. (No model.)

To all whom it may concern:

Be it known that we, CHARLES L. BALDWIN and OLLIE A. GREEN, citizens of the United States, residing at New York, in the State of New York, have invented a new and useful 5 Elevator, of which the following is a specification.

This invention relates generally to elevators, and more particularly to one designed for 10 use in the construction of buildings for the purpose of transporting wheelbarrows of brick or other material from the ground floor to the upper portions of the building and also for carrying down unloaded barrows to the ground 15 floor for reloading.

The object of the invention is to provide an elevator for this purpose in which the loading and unloading operations will be greatly facilitated, thereby enabling such operations to 20 be more quickly accomplished than heretofore.

Another object of the invention is to provide a signaling device to be used in connection with the elevator whereby the engineer 25 at the bottom of the structure is notified of the unloading of the elevator, so that the engine can be reversed and the elevator permitted to descend.

Another object of the invention is to provide 30 an elevator of such construction that the unloaded wheelbarrows can be placed thereon prior to the withdrawal of the loaded wheelbarrows and without interfering with the said loaded barrows.

Another object of the invention is to provide 35 for the automatic release and discharge of the unloaded barrows when the elevator reaches the ground floor of the construction.

With these various objects in view the invention 40 consists, essentially, in providing an ordinary elevator with a supplemental platform arranged above the main platform or floor of the elevator, said supplemental platform being adapted to receive and carry the 45 unloaded barrows, said unloaded barrows being conveyed to the said platform by means of an inclined skid, and each skid is automatically released the moment the empty barrow is properly arranged upon the supplemental 50 platform.

The invention also includes means arranged

adjacent to the ground floor of the construction whereby the supplemental platform is tilted or inclined upwardly, thereby releasing and discharging the empty barrow therefrom 55 at the same time the main platform or floor of the elevator is brought into position to receive the loaded barrow.

The invention consists also in certain details of construction and novelties of combination, all of which will be fully described hereinafter and pointed out in the claims. 60

In the drawings forming a part of this specification, Figure 1 is a perspective view illustrating the elevator as raised to the top floor 65 of the structure, the inclined skids being also raised ready to receive the unloaded barrows, the loaded and unloaded barrows being omitted from this illustration for the purpose of more clearly illustrating the construction of 70 the elevator and its parts. Fig. 2 is a bottom plan view of the supplemental platform. Fig. 3 is a detail in perspective of the skid-supporting bar as viewed from the under side. Fig. 4 is a detail sectional view of the said 75 bar, the tripping-arm connected thereto being shown in elevation. Fig. 5 is a diagrammatic elevation illustrating the complete operation of the invention, the ground and top floors of the structure being shown in section. This 80 view illustrates the position of the various parts after the elevator has arrived at the top floor of the structure, an unloaded barrow rolled up the skid, as indicated in dotted lines, and placed upon the supplemental platform. 85 Fig. 6 is a view, partly in elevation and partly in section, illustrating the operation of the supplemental platform when it reaches the limit of its downward movement, said platform being shown in the act of releasing and discharging the unloaded barrow therefrom, the loaded barrow being loaded upon the main platform of the elevator, as indicated in dotted lines to the left of the figure. Fig. 7 is a detail perspective view illustrating the end of the 90 skid. Fig. 8 is a longitudinal sectional view of said end, the dotted lines indicating the position the parts assume during the downward passage of the elevator; and Fig. 9 is a bottom plan view of said end of skid, and 95 Fig. 10 is a detail perspective view illustrating the means for adjusting the upper end 100.

The invention also includes means arranged

of the guide-bar for elevating the supplemental platform.

In the practical embodiment of our invention we employ an elevator comprising the 5 main floor or platform A, which is carried by the ordinary and usual uprights A', connected by the cross-bar A², to which the elevating-ropes A³ are attached, the uprights working, as usual, between the guides A⁴, said guides 10 extending from the bottom to the top of the structure.

Our invention, as before stated, is particularly designed for elevating and lowering wheelbarrows during the construction of 15 buildings, and in practice we prefer to make our elevators of such size that two barrows arranged side by side can be conveniently carried upon the main platform or floor, and it will of course be understood that the elevator 20 can be made of such size as to receive as many or as few barrows as the necessity of the case may require.

Upright standards B are attached to the rear corners of the main platform and extend 25 upwardly therefrom. A cross-bar B', preferably of channel-iron, is connected to the uprights A' a definite distance above the main floor or platform A. Supported upon this cross-bar B' are the channel-bars B², the 30 rear ends of said channel-bars being supported upon the cross-rod B³, which connects the upper ends of the upright standards B. Resting upon the channel-bars B² is the supplemental platform C, the timbers of which 35 are securely connected to the angle-irons C', arranged upon the under side of said platform, the rear ends of said angle-irons C' being pivoted to the cross-rod B³ upon the inner sides of the upright standards B, thereby 40 pivotally connecting the supplemental platform C at its rear end to the rod B³. The angle-irons C' normally rest upon the cross-bar B'. Inclined brace-rods B⁴ extend from the upper ends of the uprights B to the main 45 platform or floor A, thereby bracing the said standards and also serving as stops to limit the rearward movement of wheelbarrows rolled upon the main platform or floor A.

Each channel-bar B² has a slide bar or bolt 50 D arranged in its forward end and projecting a short distance beyond said forward end, said bar or bolt being held in place by means of pins D', passing through the longitudinal slots D², produced in the sides of the channel-bar, and a coil-spring D³, surrounding a pin D⁴, which works through a transverse plate D⁵, normally holds each bar or bolt in its forwardly-projecting position. These bolts or 55 bars D are adapted to engage the free ends of 60 the skids E, which are pivoted at E' to the upper floor of the structure, and owing to the engagement of the bars or bolts D with the free ends of these skids the said skids will be elevated and held in such inclined positions, 65 as most clearly indicated in Figs. 1 and 5. These skids are only arranged upon the floor where the material elevated is to be used,

and when the elevator has reached such floor and has been stopped the empty wheelbarrows are first rolled up the skids and placed 70 upon the supplemental platform C. Each bar or bolt D is provided with an upwardly-projecting arm F, which works in a slot F', produced in the supplemental platform, and said arm is of such height and shape that 75 when the empty wheelbarrow is rolled upon the supplemental platform a leg or cross-bar of the said wheelbarrow will engage the said arm, forcing it rearwardly and withdrawing the bar or bolt. Such movement of the bar 80 or bolt immediately releases its respective skid, and the said skids drop by their own weight and rest upon the floor. The empty wheelbarrows have now been securely arranged upon the supplemental platform and 85 the way is clear for the removal of the loaded wheelbarrows.

In connection with the elevator we employ a signaling operating mechanism at the upper floor, which is operated by the withdrawal of 90 the last loaded wheelbarrow from the main floor or platform of the elevator, so that the engineer can be notified when said elevator is ready to be lowered, and in arranging such signaling mechanism we employ a lever G, 95 which is pivoted between two guide-pieces G', arranged adjacent to the edge of the elevator-shaft in such a manner that as the wheel of the barrow passes between the said guides the lever G will be operated, which in turn 100 operates a lever G² by means of a rod G³, and this lever G² transmits its motion through a wire G⁴ and one or more bell-cranks G⁵ to the bell or gong G⁶. By means of this device the engineer will be notified at the proper time. 105 In case a workman is employed to remove each loaded wheelbarrow, it is intended that they shall move them simultaneously, and in case only one workman is intended to remove the two or more wheelbarrows those 110 which do not come in contact with the operating-lever will be removed first and the wheelbarrow which does come in contact with the operating-lever removed last, so that all danger of a premature descent of the elevator is avoided. As the elevator descends the forwardly-projecting bar or bolt D will 115 of course contact with the free end of the skid, and in order to compensate for such contact we provide the said skid with a pivoted end E², 120 said end being arranged in a channel-plate E³, which is pivotally connected to the rigid portion of the skid by means of a bolt E⁴, and surrounding said bolt is a coiled spring E⁵, one end of which bears against the end of the 125 rigid portion of the skid and the other end against the pivoted portion, the tendency of said spring being to normally hold the end E² in alignment with the skid E, said spring, however, permitting the end E² to be turned 130 down, as indicated in Fig. 8, during the downward movement of the elevator, thereby avoiding damage to the skid, and the moment the elevator has passed the said spring

will throw the end E^2 up to its normal position ready to receive the bar or bolt D upon its next upward movement.

Adjacent to the lower floor of the structure we arrange the guide-bars H , the lower ends being rigidly secured to the upright guides A^4 , and the upper ends of said guide-bars are secured, preferably, to the floor above the floor of the structure, and in order to compensate for different heights of floors we provide longitudinal slots H' in the upper ends of the bars H and connect the extension-bars H^2 to said slotted ends by means of bolts H^3 , the upper end of the extension-bar being bent, as shown at H^4 , to rest upon the floor.

The supplemental platform carries guide-rollers I at each forward corner, which guide-rollers are adapted to contact with the guide-bars H , and said bars H are curved in such a manner that as the elevator continues to descend after the rollers have come in contact with said guide-bars the supplemental platform C will be elevated and inclined, as most clearly shown in Fig. 6, said platform swinging upon its pivot at the rear end, and it is elevated or inclined to such an angle that the leg or cross-bar engaging the arm F is carried over the top of said arm as the arm remains stationary, while the platform is tilted, and the wheelbarrow will immediately roll from the supplemental platform upon an inclined guideway which is arranged upon the ground floor of the structure adjacent to the elevator-shaft, the upper end of said inclined guideway being in such position as to receive the wheel and legs of the empty barrow without jolting. At the same time that the empty barrow is automatically discharged from the supplemental platform the loaded barrow or barrows are rolled upon the main floor or platform of the elevator and the signal given the engineer for raising the elevator.

The elevator is then raised, and the supplemental platform resumes its normal or horizontal position upon the channel-bars B^2 and cross-bar B' as soon as it reaches a point above the guide rail or bar H . When the upper floor of the structure is reached, the operations hereinbefore described are repeated—that is, the skids are raised automatically, the empty wheelbarrow is rolled upon the supplemental platform, the skids dropped automatically, and the loaded wheelbarrows withdrawn from the lower or main platform of the elevator, one of said wheelbarrows operating a signal notifying the engineer that the unloaded barrows have been placed upon the elevator and the loaded barrows removed therefrom.

It will thus be seen that we provide an exceedingly simple and efficient construction of elevator capable of carrying out all the objects hereinbefore mentioned.

Having thus fully described our invention, what we claim as new, and desire to secure by Letters Patent, is—

1. An elevator having a supplemental platform arranged above the main floor or platform, said supplemental platform being hinged or pivoted at its rear end, substantially as described. 70

2. An elevator having a supplemental platform arranged above the main floor or platform, and the inclined skids leading to the said supplemental platform, substantially as 75 described.

3. An elevator having a supplemental platform arranged above the main floor or platform in combination with the hinged skids adapted to rest upon the supplemental platform, and means for automatically releasing the said skids, as set forth. 80

4. An elevator having a supplemental platform arranged above the main floor or platform and pivoted at its rear end, in combination with means for elevating and inclining the said supplemental platform for the purpose described. 85

5. An elevator having a supplemental platform arranged above the main floor or platform, in combination with the hinged skids, and the spring-actuated bars or bolts carried by the supplemental platform adapted to hold the said skids elevated, and means for releasing said bars or bolts, substantially as set forth. 90

6. An elevator having a supplemental platform arranged above the main platform or floor, said supplemental platform being provided with forwardly-projecting spring-actuated bars or bolts, each bar or bolt having an upwardly-projecting arm working in a slot produced in the platform in combination with the hinged skids, each skid having a hinged end, for the purpose described. 100 105

7. The combination with the elevator having a supplemental platform arranged above the main floor or platform, said supplemental platform being pivoted at its rear end and provided with guide-rollers at its forward ends, of the inclined side bars upon which the guide-rollers are adapted to travel whereby the supplemental platform is elevated or inclined, for the purpose described. 110

8. The combination with the elevator having a supplemental platform arranged above the main platform and pivoted at its rear end and provided with guide-rollers at its forward end, of the guide-bars with which the guide-rollers are adapted to contact, said guide-bars having the adjustable extensions at their upper ends, as and for the purpose described. 115 120
